BUILDING MATERIAL

Norman P. Harshberger, Scarsdale, N. Y., assignor
to Bakelite Building Products Co. Inc., New
York, N. Y., a corporation of Delaware

Application June 11, 1930, Serial No. 460,409

6 Claims. (Cl. 108—7)

This invention relates to improvements in building material and method of producing shaded effects thereon, and is a continuation in part of my copending application Ser. No. 279,402 filed 5 May 21, 1928.

It is one of the objects of this invention to provide an improved building material in which the surface thereof is formed in a novel manner to create shadow effects in certain areas so as to 10 simulate designs or lines of demarcation.

A further object of this invention is to provide an improved method of producing shaded effects in which certain portions of the surface of the material are raised, said raised portions 15 creating shadow effects.

A more specific object of this invention is to provide improved building material and method of producing shaded effects thereon in which asphalt is applied in spaced apart dot-like formation to create a plurality of raised portions which 20 will produce shadows.

A further object of this invention is to provide improved building material having certain portions of its area raised so as to space a superimposed unit therefrom when said units are laid on 25 a roof to create air spaces for insulation purposes.

A further object of the invention is to provide improved building material which is simple and inexpensive to manufacture, attractive in appearance, and well adapted for the purpose described. 30

With the above and other objects in view, the invention consists of the improved building material and method of producing shaded effects thereon, and all its parts and combinations as set 35 forth in the claims, and all equivalents thereof.

In the accompanying drawing illustrating one complete embodiment of the preferred form of the invention, in which the same reference numerals designate the same parts in all of the views:

Fig. 1 is a plan view of a strip of the improved roofing material;

Fig. 2 is a sectional view taken on line 2—2 of Fig. 1;

Fig. 3 is a plan view showing a pair of overlapping units as they appear when laid on a roof; and

Fig. 4 is a sectional view taken on line 4—4 of Fig. 3.

Referring to the drawing, the numeral 8 designates a strip of the usual composition building material which comprises a fabric base 9 such as felt, having a coating of asphalt 10 applied thereto and having crushed mineral material 11 such as slate sprinkled over the asphalt and partially 55 embedded therein.

To create the novel design effect, additional asphalt is applied in dot-like formation as at 12, said dots being spaced from one another and being arranged in desired lines as shown in Fig. 1, or in certain areas as shown in Fig. 3. Additional crushed mineral material 13 is applied over said raised portions 12.

The raised dotted areas will naturally create shadows on the material and when a group of the units laid on a roof is viewed from a distance, 10 the effect will be substantially the same as though the designs or lines of demarcation were formed by using mineral material of two different shades. In the present invention, mineral material of one shade only is used, and the effect is accentuated 15 by the shadows produced by the raised portions.

The groups of spots 12 may be formed so that the edges thereof will be suitable for associating with the edges of a strip to form desired figures. Also they may be formed by means of a cellulose 20 material such as Duco, which readily dries, and hence will not stick to the other side of the strips as they are wound up into rolls. Or these spots may be produced as raised figures by means of a bituminous mineral only or in any other suitable manner.

If desired, the staggered raised areas may be applied over the entire surface of the material, thereby producing a two-tone effect throughout.

An advantageous feature of the invention is 30 illustrated in Fig. 4 wherein it may be seen that when two units are placed in overlapping position on a roof, that an air space 14 is created therebetween which will serve as additional insulation and which will prevent sweating between 35 the elements.

It is to be understood that the raised portions may be applied in any arrangement desired and they may be utilized on building material of any shape. It is further to be understood that the 40 invention contemplates in addition all other changes and modifications which may come within the scope of the claims.

What I claim is:

1. As an article of manufacture, flexible roofing 45 material comprising a composition base, a substantially flat and even bituminous adhesive layer on said base presenting an interspersed-mineral layer, and a plurality of individual disconnected mineral surfaced bituminous overlays spaced in 50 substantially close relation to each other over said mineral layer and grouped to form distinctive shingle effects and dividing said base into shingle configurations some composed of the mineral layer and others composed of said grouped 55

overlays, the shadow effect cast by said overlays serving to aid in distinguishing said configurations from one another.

2. As an article of manufacture flexible roofing material comprising a composition base, a substantially flat bituminous adhesive layer on said base presenting an interspersed-mineral layer and a plurality of individual disconnected mineral surfaced overlays of additional material having closed peripheries in the plane of the base, spaced in substantially close relation to each other over said mineral layer and grouped to form broken lines dividing said base into similar shingle configurations comprising the mineral layer, the shadow effects cast by said overlays combining therewith in assembly to form effective lines of demarcation for said configurations.

3. A roof comprising a plurality of shingle elements of flexible roofing material each comprising a composition base having a substantially flat and even mineral surface layer thereon and having a plurality of individual, disconnected substantially small overlays of other material spaced in substantially close relation to each other over said surface layer and grouped to form distinctive shingle effects and dividing said base into shingle configurations some composed of the mineral layer and others composed of said grouped overlays, the shadows cast by said overlays serving to accentuate the distinction between shingle configurations and said elements being laid in overlapping position with the overlays serving to register the configurations and to create connecting pockets and spaces between the contacting overlapping portions to aid in the air circulation and insulation of the roof.

4. In a roofing assembly a plurality of overlapping shingle elements of flexible roofing material each comprising a composition base having a substantially flat and even adhesive layer thereon presenting a mineral layer of interspersed-mineral particles and having a plurality of individual, disconnected, mineral surfaced bi-

tuminous overlays spaced in substantially close relation to each other over said mineral layer and grouped to form distinctive shingle effects and dividing said base into shingle configurations some composed of the mineral layer and others composed of said grouped overlays, the shadows cast by said overlays serving to accentuate the distinction between shingle configurations and said elements being laid in overlapping courses with the overlays serving to register the configurations so as to produce vertical rows and horizontal courses of alternating shingle effects and providing connecting cells and spaces between the contacting overlapping portions for air circulation and thermal insulation.

5. As an article of manufacture, roofing material comprising a composition base, having a substantially flat water-proofing layer thereon gripping a granular surfacing, and a plurality of individual disconnected raised portions of additional material having closed peripheries in the plane of the base, spaced in substantially close relation to each other over the surface of said base and grouped to form broken lines dividing said base into shingle configurations, the shadow effects cast by said raised portions combining therewith in assembly to form effective lines in demarcation for said configurations.

6. As an article of manufacture, roofing material comprising a composition base, a substantially flat adhesive layer comprising bitumen on said base presenting an interspersed mineral layer, and a plurality of individual disconnected overlays of additional material including a granular wear resisting facing spaced in substantially close relation to each other over said mineral layer, said overlays casting shadow effects in assembly when laid in overlapping courses to accentuate the configurations formed and to create connecting pockets and spaces between overlapping portions to aid in the air circulation and insulation of the roof.

NORMAN P. HARSHBERGER.
